(57) **CLAIM**

The ornamental design for a detergent container, as shown and described.

DESCRIPTION

FIG. 1 is a perspective view of embodiment one, of a detergent container, showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof;

FIG. 8 is a perspective view of embodiment two, of a detergent container, showing our new design;

FIG. 9 is a front view thereof;

FIG. 10 is a rear view thereof;

FIG. 11 is a right side view thereof;

FIG. 12 is a left side view thereof;

FIG. 13 is a top plan view thereof; and,

FIG. 14 is a bottom plan view thereof.

(Continued)

The broken line portions show unclaimed subject matter only and form no part of the claimed design.

1 Claim, 8 Drawing Sheets
